FUSIBLE TRIP MECHANISM FOR AUTO-MATIC CUTOFF VALVES

Herbert H. Shiels, Culver City, Calif.

Application April 21, 1950, Serial No. 157,221

5 Claims. (Cl. 137—75)

1

This invention relates to valve mechanism for pipe lines carrying gas, oil, ammonia, steam or other fluids into buildings, under pressure, and has particular reference to emergency closing means for such valves.

It is the general object of the invention to provide closing means for such valves which includes and is actuated by a collapsible element. It is a further object of the invention to provide a valve and valve control mechanism both of which are leak-proof not only while the valve remains in normal open position but also when, after an emergency has caused it to be closed, it has to be reset for continued operation. A still further object is to provide improved means for facilitating the resetting of such valve mechanism. Another object of the invention is to provide improved means which is very sensitive to heat to the end that the emergency of the closing of the valve may take effect upon relatively small predetermined temperature rise.

Another object is to provide valve closing means which is controllable from points outside of the building within which the valve is placed.

These and other objects of the invention will be better understood from the following detailed description particularly when reference is had to the accompanying drawings in which preferred forms of the invention are illustrated. In the drawings:

Fig. 1 is a cross-sectional view substantially through the vertical center of the device embodying the invention;

Fig. 2 is a similar view showing the valve control mechanism similar to that of Fig. 1 but attached to a different type of valve; and

Fig. 3 illustrates diagrammatically a modified form of actuating means for the valve control.

Referring in the first instance to Fig. 1, it is noticed that the numeral 1 designates a valve casing having a fluid passage 2 therethrough and a valve seat 3 in the center of this passage. A cylindrical bore 4 extends from the top of the casing vertically downward into this passage in axial alignment with the said valve seat. The upper end of this bore is internally provided with screw threads 14 of a size to receive therein the threads of a cap 5 which tightly closes the entrance to this bore. The cap extends downward a distance below the screw threads thereof to provide therein a cylindrical chamber 6 within which a valve stem 7 is fitted for axial sliding movement. The stem terminates at the lower end thereof in the valve 8 and this valve is, by means of a plunger 16 engaging an annular groove 9 between the

2

stem and the valve head, maintained in the withdrawn position shown in Fig. 1. A spring 11 urges downward movement of the valve stem to close the valve.

To the side of the casing 1 is shown secured a box-shaped frame 15, forming a chamber 16 within which the valve control mechanism is mounted in the following manner. Into the central portion of this chamber extends a portion 17 of the valve casing and a cylindrical recess 18 is sunk into the inner face of this casing extension in axial alignment with the plunger 10. The latter is shown fitted with a head 19 of a size to slide freely within this bore and a spring 20 within the bore urges the plunger away from the valve stem. Such inward movement of the plunger is checked by means of lever connections which for the purpose of illustration are shown to include an inner lever 25 pivotally mounted at 26 on a lug 21 of the casing member 17. A knob 22 of this lever contacts a diaphragm 27 which tightly closes the entrance to the bore 18 and this knob is in axial alignment with the enlarged central portion 28 of the plunger head 19. From this description it is seen that the spring 20 urges the plunger and the diaphragm 27 against the knob 22 of the lever.

A second boss 30 extends inwardly from the casing portion 17 to provide a pivotal support 31 which is positioned diametrically opposite the pivot 26. A second lever 32 extends from the pivot 31 parallel with the lever 25 and diametrically in the opposite direction. The lever 32 is at the outer end thereof shown fitted with a head 33, which is by means of a screw 34 seated in the end thereof fitted to receive a fusible element 35. A boss 36 rises from the casing portion 17 and this boss is similarly fitted to receive the opposite end of the fuse 35. A screw 37 extends through the inner end of the lever 32 and the end of this screw is shown contacting the outer end of the inner lever 25. This completes the control mechanism of the valve.

It should be clear to anyone versed in the art that the pressure of the spring 20 against the inner surface of the plunger head 19 together with the fuse 35 maintain the above described lever connections in the position indicated in Fig. 1. It is furthermore important to note that the pressure of the spring 20 is sufficient quickly to move the levers to withdraw the plunger 10 from the groove 9 of the valve stem when the rising temperature causes the fuse element 35 to melt. It is also equally important to note that due to the relative positions of the levers 25 and 32 the

pressure of the spring 20 becomes gradually reduced to such an extent that the tension on the fuse element 35 is negligible. It is for this reason possible to make use of an extremely flimsy fuse element which will surely collapse the moment the temperature surrounding the valve reaches a predetermined degree of heat.

While in Fig. 1 is illustrated a conventional type of globe valve for controlling a conduit carrying a gaseous fluid and which is designed quickly to snap into closed position in response to undue rise in temperature, I have found it possible to adapt the same type of valve control mechanism to the type of valve normally employed to control the flow of liquids, such as oil, through a conduit. This type of mechanism is, in Fig. 2, shown to include a valve casing 40 to the side surface of which a box-shaped frame 41 is secured in the same manner that the frame 15 is mounted in position on the valve casing 1 and this frame may be identical with the frame 15. The control mechanism within the framing may also remain substantially as above described and it is in like manner fitted with a plunger 42 which is placed in position normally to maintain the valve stem 43 in retracted position. However, the valve is, in this view of the drawing, shown tripped in order better to illustrate the positions taken by the levers 25 and 32 when the temperature rise causes the fuse to melt.

From the valve 43 rises a threaded shank 44 which, in turn, is held rigidly in position in the screw threads of a thimble-shaped valve stem 45 and the latter is fitted to slide axially within the bore 46 of the casing. A spring 47 urges the valve into the closed position of Fig. 2. It is noticed that the shank 44 is undercut to provide an annular groove 48 of a size to receive the end of the plunger 42 when the valve is raised into open position, as will now be described. A cap 50 closes the entrance to the casing bore 46 and this cap is axially perforated to receive the reduced portion of a stem 52. Suitable means, such as a nut 53 engages the threaded end of the stem to lock it rigidly in position in the cap. This stem extends through and is slidably fitted within the head 54 of the valve stem. To the lower end of the stem is rigidly secured a cylindrical head 55 forming a piston which is fitted to slide within the cylindrical bore 56 of the valve stem. A portion of this piston is broken away in order to illustrate that it is fitted with a number of perforations 57. The space within the valve stem is filled with a heavy oil, or the like, before the valve is screwed into position therein.

While the valve remains in the closed position of Fig. 2, no fluid can pass through the conduit 60; nor can any portion of the liquid leak out of the valve casing when the parts are properly proportioned and fitted together. When it is time to reopen the valve, it is merely required to unscrew the cap 50 and to continue the withdrawal movement until the plunger 42 reaches a position of alignment with the annular groove 48. The frame or cover 41 has at the same time been removed from the valve case by withdrawal of the fastening screws 60, 61. If the levers 25, 32, by finger pressure, are lightly urged toward the position shown in Fig. 1, it is found that the plunger 42 will slide into the annular groove 48 the moment it reaches the position of registration therewith. The valve is now held in open position and a new fuse may be applied to lock it permanently in open position. The cap 50 may then be reseated tightly to enclose the valve mechanism.

The purpose of placing the foraminous piston 55 within the oil filled valve stem is to slow down the closing movement of the valve as generally found necessary in this type of equipment. In order to maintain the valve in proper alignment with its seats, it is well to provide means for locking the valve against rotation within the casing. Such means may, for the sake of illustration, take the form of a pin 64 of the casing extending into an axial groove 65 which is sunk into the peripheral surface of the valve stem.

It is above stated that it is one of the objects of the present invention to provide means for controlling the valve closing mechanism from points outside of the building within which the valve is placed. Illustrative of such means I have, in Fig. 3, shown the outer levers 32 of Figures 1 and 2 replaced by a lever 70, to the upper end of which a pawl 71 is pivotally secured. The outer end of this pawl is shaped to engage a boss 72 which takes the place of the boss 36 of the casing member 17.

A rod or wire 73 extends from the pawl to the core 74 of a solenoid magnet 75 which latter may be suitably positioned on top of the casing 15 or 41. This magnet is cut into a circuit extending through a source of energy 76 at a remote point outside of the building. A normally open switch 77 is provided to control this circuit and this switch may be manually closed to energize the magnet thereby to withdraw the pawl and so to release the control mechanism for closing movement of the valve. It may be found advantageous to provide means, such as a spring 78, more securely to maintain the pawl 71 in engagement with the boss 72. When the perforation of the pawl, through which the end of the rod 73 extends, is elongated substantially as indicated at 79, it is found that the lever 70 is afforded more freedom to swing into the valve closing position of Fig. 2.

While I have above described preferred forms of the invention it should be clear to anyone familiar with the art that modifications of proportions and arrangements may be embodied therein without departing from the spirit of the invention. It is the intention therefore to be limited only as indicated by the scope of the claims hereto appended.

I claim:

1. A valve mechanism comprising, a casing having a valve seat therein, a valve slidable in the casing, resilient means urging said valve toward the said seat, a plunger engaging the valve to maintain it in open position, resilient means urging said plunger away from the valve, a diaphragm abutting the outer end of said plunger and closing an opening of the casing at the end of the plunger, diaphragm contacting means including two levers, each pivotally mounted at one end thereof on the casing, one lever having intermediate its ends a knob contacting said diaphragm, the other lever having intermediate its ends a projection contacting said first named lever, and fusible means locking the two levers in position to maintain the plunger in engagement with the valve.

2. A valve mechanism comprising, a casing having a valve seat therein, a valve slidable in the casing, resilient means urging said valve toward the said seat, a plunger engaging the valve to maintain it in open position, resilient means urging said plunger away from the valve, a diaphragm abutting the outer end of said plunger and closing an opening of the casing at the end

of the plunger, a lever pivotally mounted at one end thereof on the casing and contacting the outer surface of the diaphragm, a second lever pivotally mounted at one end thereof on the casing, the pivoted end portion of which contacts the free end of said first named lever, and a fusible element extending from the casing to the free end of said second lever for locking the levers in position to maintain the plunger in engagement with the valve.

3. A valve mechanism comprising, a casing having a valve seat therein, a valve slidable in the casing, resilient means urging said valve toward the said seat, a plunger engaging the valve to maintain it in open position, resilient means urging said plunger away from the valve, a diaphragm abutting the outer end of said plunger and closing an opening of the casing at the end of the plunger, a lever pivotally mounted at one end thereof on the casing and contacting the outer surface of the diaphragm, a second lever pivotally mounted at one end thereof on the casing, an adjustable element at the inner end thereof contacting the free end of said first named lever, and a fusible element extending from the casing to the free end of said second lever for maintaining the plunger in engagement with the valve.

4. A valve mechanism comprising, a casing having a valve seat therein, a valve slidable in the casing, said valve having an annular groove intermediate its ends, resilient means urging said valve toward said seat, a plunger engaging the groove of the valve to maintain it in open position, resilient means urging said plunger away from said valve, a lever assembly pivotally mounted on the casing and movable to advance said plunger into the said groove, a diaphragm intersecting said plunger and lever assembly and seat-

ed in an opening of the casing tightly to close the interior of the casing from the exterior thereof, and a fusible element normally locking the lever assembly in position to maintain the plunger advanced.

5. A valve mechanism comprising, a casing having a valve seat therein, a valve slidable in the casing, resilient means urging said valve toward the said seat, a plunger engaging the valve to maintain it in open position, a spring urging said plunger away from the valve, a diaphragm abutting the outer end of said plunger and closing an opening of the casing at the end of the plunger, a lever pivotally mounted at one end thereof on the casing and having intermediate its ends a boss contacting the outer surface of the diaphragm, a second lever pivotally mounted at one end thereof on the casing, an adjustable element in said second lever contacting the free end of said first named lever, a boss on the casing, a clamping screw in said boss, a clamping screw engaging the free end of said second lever, and a fusible element engaged by said clamping screws to lock the levers in position to maintain the plunger advanced.
